SEPARATING STRIPS FOR WALL JOINTS

Robert E. Dudley, Bellevue, Wash., assignor to Tracey, Cook, Brunstrom & Dudley, Seattle, Wash., a partnership

Filed Apr. 5, 1961, Ser. No. 100,974

3 Claims. (Cl. 20—74)

The present invention relates to separating strips to be placed between adjacent edges of panels forming a wall whether such edges extend vertically or horizontally.

The principal object of the present invention is to provide separating strips which will seal the joints between wall panels of plywood to prevent moisture from running or even from infiltrating into the joints between adjacent panels whether such joints extend vertically or horizontally.

In thus sealing wall joints it is an object to provide such separating strips which will fit the panel edges even though the thickness of adjacent panel edges may be somewhat different or such edges vary somewhat in thickness, or are otherwise irregular. Moreover, such strips will not prevent expansion or contraction of the panel edges at the joint caused by atmospheric changes in temperature or humidity, or both.

It is also an object to provide such separating strips which can be retained in a panel joint by the panels and without requiring separate mounting.

Another object is to provide such separating strips which can be fitted to a wall joint and installed quickly and easily during the installation of the wall, and which do not require any special preparation of the panel edge or wall to accommodate such separating strips.

Although economical to produce, such separating strips are very durable and not easily damaged either before, during or after installation in a wall joint.

A further object is to provide such separating strips which will be attractive in appearance but when colored to match the wall will be unobtrusive. Alternatively, such strips can be of a color contrasting with the color of the wall to produce a decorative effect.

Separating strips for accomplishing the foregoing objects should be adapted for installation in substantially the same manner both in vertical joints and in horizontal joints of a wall. Such strips are made of extruded pliable sluggishly elastic plastic material of modified H-beam cross section. Each strip has a web engageable between the edges of adjacent panels and a wide flange on one edge of such web having portions extending equal distances oppositely from the web. Such wide flange is fitted behind the adjacent panel edges. At the exposed side of the wall the vertical strips have crested flanges, the edge portions of which engage and are flattened against the adjacent edge portions of the panels forming the joint. At the exposed side of the wall the horizontal strip has a downwardly extending flange engageable with the lower panel face and a drip projecting outwardly and downwardly from the web of the strip and the root of the downwardly projecting flange.

FIGURE 1 is an elevation of the exposed face of a wall section including strips of the present invention.

FIGURE 2 is an enlarged bottom perspective of a portion of such a wall showing a stretch of horizontal joint and a stretch of vertical joint.

FIGURE 3 is a horizontal section through a vertical joint taken on line 3—3 of FIGURE 2 and FIGURE 4 is a vertical section through a horizontal joint taken on line 4—4 of FIGURE 2.

FIGURE 5 is a transverse section through a separating strip for an upright joint in relaxed condition.

FIGURE 6 is an elevation of an exposed wall section face showing an arrangement of joints and strips different

2

from that of FIGURE 1, and FIGURE 7 is an enlarged bottom perspective of such a wall showing horizontal and vertical joint portions.

The separating strips of the present invention can be made of different size depending upon the thickness of the wall panels. Such separating strips are particularly useful for sealing the joints between plywood panels used as a wall facing. Such plywood panels may, for example, be one-half inch, five-eighths inch or three-quarters of an inch in thickness to be used without exterior covering as a surface providing adequate structural strength to withstand wind and weather loads and wall rigidity when properly secured to the wall framing. Preferably the plywood sheets are of exterior grade because they are water-proof.

When plywood is used for the exterior wall surface the panels 1 are formed of rather large sheets of plywood, a conventional size being 4 feet by 8 feet. Such sheets can be applied so that the length of each sheet extends vertically, as shown in both FIGURE 1 and FIGURE 6 of the drawings, or horizontally, depending upon the shape and size of the particular wall. In either case the framing structure on which the surface sheets are mounted is in the form of a grid so that the edges of each plywood sheet will be backed by frame members 2 spanning both the vertical joints 3 and the horizontal joints 4. The edge portions of the plywood sheets 1 are then nailed to the framing members 2 at sufficiently close intervals so that each panel will be secured adequately about its edge. The panel will be inherently sufficiently stiff so that the central portion of the panel will not be easily bendable appreciably when the panel edges are thus backed.

Where plywood sheets are secured to such a framing structure they can be applied most readily by simply butt joining their edges so that the outer faces of adjacent panels are flush. Since there is no overlap of the panel edges at the joints, the problem is presented of making such joints water-tight. One customary procedure has been to caulk such joints with some type of calking material. If this material is in the form of a paste it is difficult to apply it so that it will penetrate into the joints and such paste material is inclined to dry out and become brittle or to be forced out by working of the panel edges as they swell or shrink, caused by temperature or humidity changes. Alternatively, the joints between the panels can be calked with fibrous calking material, such as calking cotton. Use of either type of calking material requires considerable labor. Alternatively, the joints can be covered with wood or metal battens, but it is then necessary to seal the joints between the battens and the panels, in many cases. Moreover, the application of such battens also involves considerable work and the completed structure is considered to be unsightly by many people.

The strips of the present invention provide weather-tight joints between the panels 1, both vertically and horizontally. Such strips are of modified H-beam cross section including a web portion 5 which serves as a separating strip between the adjacent edges of adjacent panels. Wide flanges 6 integral with one edge of the web 5 extend in opposite directions from such web to form a planar flange to be located at the inner side of the wall facing. These flanges can be interposed between the edge portions of the sheets 1 and the framing members 2. When the plywood sheets are nailed to the framing members the inner flanges of the separating strips will be clamped between the panel edges and the framing members to hold the strips securely in the joints.

On the opposite edges of the strip webs 5 are flanges which differ in the strips for the horizontal joints and the vertical joints. The strips for the vertical joints have a crested flange including oppositely extending flange por-

tions 7 meeting at a salient angle 8. In such vertical strips the width of the web 5 will be considerably greater than the thickness of the plywood sheets forming the joint, as shown in FIGURES 2 and 3. The flange portion 7, and preferably the entire strip, will be made of pliable material such as extruded vinyl plastic of 90 durometer hardness.

When the vertical strip is in relaxed condition, as shown in FIGURE 5, the edges of the flange portions 7 will be spaced from the flange portions 6 a distance substantially less than the thickness of the plywood sheets 1. Consequently, when these strips are assembled in the joint with the edge portions of the panels received between the opposite flanges, the edge portions of flange 7 will be flattened against the outer surfaces of the panels, as shown in FIGURES 2 and 3. The side portions of the crested flange will therefore assume a somewhat concave shape, as shown in FIGURES 2 and 3. In order to insure flat contact of these flange portions with the faces of the panels over a considerable width, the flange portions 7 are tapered in thickness toward their edges. Without such tapering the bending of such flanges would tend to occur principally adjacent to the web 5 when pressure is applied to the flange edge, instead of the entire flange portion forming a gradual curve, as shown in FIGURES 2 and 3.

The value of the salient dihedral angle 8 measured between the outer surfaces of the flange portions 7 when they are in the relaxed condition of FIGURE 5 should be approximately a right angle, the angle shown being about 80°. If such angle is too small, the curvature of the flange portions 7 will be sharper than desirable, while if the salient angle is too large either the web 5 may be shorter than desired, or the width of the flange portions 7 may be greater than desired or the edges of such flange portions may press against the surface of the sheets 1 with less pressure than desired. Consequently, such salient angle should be within the range of 60° to 100° in order to provide the most desirable type of joint-covering batten.

The horizontal separating strip has a downwardly projecting flange 9 spaced from the lower inner flange 6 along web 5 a distance approximately equal to the thickness of a panel 1. The flange 9 will therefore closely overlie the outer surface of the edge portion of the panel immediately beneath it. This strip has no outer flange projecting upward from it, however, because a crevice would be formed between such flange and the outer surface of the edge portion of the panel immediately above the strip into which moisture could flow, which would then tend to flow along the upper surface of the strip web 5 into the joint. Instead, this strip has a drip 10 extending outwardly and downwardly from the outer edge of the web 5 preferably of curved shape. Water running down the panel above the strip would therefore flow along the upper surface of such drip away from the wall so that it would tend to drop clear of the surface of the panel below the joint.

Preferably the flange 9 and the drip 10 project downward from the web 5 equal distances so that at an intersection of a vertical joint with a horizontal joint as shown in FIGURE 1, the upper end of a square cut vertical strip can butt against the lower edges of both the flange 9 and the drip 10. While it is not necessary in such a joint, it is preferable to cut out either a portion of the inner lower flange 6 of the horizontal strip or the end portions of the inner flanges 6 at the upper end of the vertical strip, so that such flange portions will not overlap. It is not objectionable if the inner flange portions of such vertical and horizontal strips are spaced somewhat. Also, it is desirable for the distance between the inner flanges 6 and the outer edge of the drip 10 of the horizontal strip to be at least as great as the distance between the inner flange 6 and the apex of the salient angle 8 of the vertical strip so that the crest of the vertical strip will not project beyond the drip 10 above it

at a joint. Such disposition of the strips at a joint will prevent water from running off a drip into the cavities of the vertical strip behind the flange portions 7 which are located below a horizontal strip. Where a horizontal joint intersects a vertical joint as in FIGURES 7 and 8 the ends of the horizontal strip flanges 9 simply butt against the edges of the upright strip flange 7.

The wall joint sealing strips described above can be installed quickly and easily. A horizontal strip can be applied to the upper edge and a vertical strip to one side edge of a panel to be installed. The lower edge of the panel can then be set on the upper edge of a lower panel previously installed and which edge is covered by a horizontal strip. The uncovered upright edge of the panel will then be fitted with a previously installed vertical strip by bending outward the edge of the outer flange portion 7 sufficiently to receive the panel edge. Such upright edge and the lower edge of the panel may then be nailed in place. Next, the opposite upright edge of the panel may be nailed in place from the bottom up, making sure that the vertical strip which has been applied to it is pushed onto the panel edge so that its web 5 abuts such panel edge. Finally, the upper edge of the panel will be secured in place after making sure that the horizontal strip is pressed fully downward onto the upper edge of the panel.

While such method of panel installation will be satisfactory, the strip material can be made available in long indeterminate lengths and it is preferable for the separating strips to have as few joints as possible. As shown in FIGURE 1, it is preferred that the vertical joints in adjacent rows of panels be staggered so that the length of each vertical separating strip will be approximately equal to the vertical extent of a panel. The horizontal separating strips can, however, extend continuously across a plurality of vertical joints. Consequently, instead of applying a cut piece of horizontal strip to the upper edge of each panel, a row of panels can be applied to the framing structure and secured temporarily in place by nailing them only part way up from the bottom. A continuous strip can then be applied to the upper edges of the panels in the row and the upper edges of the panels then nailed to the framing to secure such strip in place before the next higher row of panels is applied.

It will be evident that the spacing between the inner flanges 6 and the outer flanges 7 and 9 should be such as to enable a horizontal or vertical separating strip to be applied to the edge of the panel and retained on it by the slight clamping action of the flanges. The strips are not secured to the panel edges, however, but are held in place simply by the flanges 6 being clamped between the panel edges and the framing structure to which they are secured. If desired, and particularly where the length of the panels extends vertically, the panels can be secured in place by nails driven along only their opposite upright edges and such nails can be driven sufficiently close to the panel edges so that the heads of the nails will be covered by the outer flange portions 7 of the upright separating strips. Such flange portions can be pulled out and bent backward locally sufficiently to enable nails to be driven at such locations. The heads of the nails are thus protected from rusting, as well as being concealed to improve the appearance of the exposed wall surface, by the bottom flange portions 7.

Since the strips are not nailed to the panels relative movement of these components can occur freely as the dimensions of the panel edges are altered by temperature or humidity changes. The vinyl material of which the strips are made is extremely resistant to deterioration by wide fluctuations in temperature and by change in moisture conditions. Also, while this material is very pliable it is not sufficiently limp so that wind would be apt to blow the flanges 7 of the vertical strips away from contact with the panel surfaces. Other types of plastic material which would be sufficiently durable and

capable of conforming to surface irregularities of the panels could, however, be used satisfactorily.

I claim as my invention:

1. In a panelled wall surface, intersecting horizontal and vertical wall joints, each comprising a unitary separating strip of pliable plastic material including a web and a pair of inner flanges extending oppositely in coplanar relationship from the inner edge portion of said web, panels having adjacent edge portions substantially abutting the opposite sides of said separating strip webs, respectively, and respectively engaging the oppositely extending portions of said inner flanges of said strips and thereby holding said strips in place, the separating strip in a vertical joint further including a crested flange having oppositely extending flange portions with their edge portions engaging the outer surfaces of adjacent panel edge portions, respectively, and their root portions spaced outwardly from such outer surfaces of the panel edge portions and the separating strip in an intersecting horizontal joint including a drip flange projecting outward and downward from the outer edge portion of the web of such strip, said drip flange being disposed adjacent to and overlying the crested flange of a separating strip in a vertical joint immediately beneath such horizontal separating strip with the edge portion of said drip flange spaced outwardly from the portion of the outer panel surface underlying said drip flange.

2. In a panelled wall surface, intersecting horizontal and vertical wall joints, each comprising a unitary separating strip of pliable plastic material including a web and a pair of inner flanges extending oppositely in coplanar relationship from the inner edge portion of said web, panels having adjacent edge portions substantially abutting the opposite sides of said separating strip webs, respectively, and respectively engaging the oppositely extending portions of said inner flanges of said strips and thereby holding said strips in place, the separating strip in a vertical joint further including a crested flange having oppositely extending flange portions with their edge portions engaging the outer surfaces of adjacent panel edge portions, respectively, and their root portions spaced outwardly from such outer surfaces of the panel edge portions the separating strip in an intersecting horizontal

joint including a flange projecting downwardly from the web alongside the outer surface of a panel edge immediately beneath the web of such strip and a drip flange projecting outward and downward from the outer edge portion of such web, said drip flange being disposed adjacent to and overlying the crested flange of a separating strip in a vertical joint immediately beneath such horizontal separating strip, the projection of said drip flange outwardly from the outer surface of the wall being at least substantially as great as the projection of said crested flange outwardly from the outer surface of such wall and the edge portion of said drip flange being spaced outwardly from the portion of the outer panel surface underlying said drip flange.

15 3. The combination defined in claim 2, in which the outer flange projecting downward from a horizontal separating strip and the drip flange of such separating strip project downward to approximately the same level, the upper end of the separating strip in the vertical joint immediately beneath such horizontal strip has an upper end portion cut substantially square and the upper end of such vertical strip is substantially in abutment with the lower edges of the outer flange and the drip flange of the horizontal strip.
